UNITED STATES PATENT OFFICE

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA

RIB-KNITTING MACHINE

Application filed November 16, 1928. Serial No. 319,816.

One object of the invention is to provide a rib knitting machine capable of producing fine gauge fabric which shall be free from the difficulties attending dividing for pressing on the second row of needles, and which also shall be free from the objection in latch needle practice of interference of latches when fine gauges are sought to be produced in rib fabric.

10 In carrying out the invention, I employ one row of spring needles and a row of co-operating latch needles. I prefer to use spring needles for the first row, to which the yarn is fed, and the second row is of 15 latch needles to which the yarn is fed by the spring needles of the first row.

Another object is to secure visibility of the knitting elements, one purpose here being to enable fabric to be readily placed on 20 the needles for starting the knitting of the goods.

A further object is to provide means of simple construction for lifting the dial and its cap away from the cylinder to gain ready 25 access to the needles of the inner row.

Other objects will appear from the following description and appended claims.

In the drawings:

Figure 1 is a central vertical sectional view 30 of a machine embodying the invention.

Fig. 2 is a detail plan view of part of the main bracket in which the center post is supported.

Fig. 3 is a vertical sectional view of part 35 of the cylinder and dial with the needle cam supports and the knitting needles, the section being taken substantially at the point where the yarn is fed to the spring beard needles.

40 Fig. 3^a is a view of the needles in their relation at the point where the spring beard needles are feeding the yarn to the latch needles of the second row.

Fig. 4 is a sectional view like Fig. 3 but 45 taken at a point where the beard presser is located.

Fig. 5 is a side elevation of a detail showing the presser and the yarn feeding finger.

50 Fig. 5^a is a bottom plan, Fig. 5^b a front

edge view, and Fig. 5^c a rear edge view of the presser.

Fig. 6 is a developed view of the cylinder cams for operating the latch needles.

Fig. 7 is a bottom plan view of the cam set for operating the spring beard needles.

Fig. 8 are views relating to the yarn guide and its support.

The invention is shown in an embodiment 60 of the rotary type in which 1 indicates the needle cylinder, 2 the cam box belonging thereto, 3 the dial and 4 the dial cap which supports the cams, as 5, for operating the dial needles. The machine may have a plurality of feeds, in which event there would 65 be a cam set for each feed.

The needles 6 which are slideable in the dial, individually as usual, are of spring beard type. The cylinder needles 7 are of the latch type. Sinkers 8 cooperate with 70 the spring beard needles to measure off the loop lengths. These sinkers reciprocate vertically in a bed 9 attached to the cylinder 1. The cam ring for the sinkers is shown at 10. The cams are indicated at 11. The 75 knitting operation is carried on in the usual manner. The yarn is fed to the spring beard needles by a tubular yarn guide finger 12, which directs the said yarn beneath the hook of the sinkers so that as the sinkers go 80 down seriatim, they will measure off the loop lengths across the stems of the advanced spring beard needles, so that as these recede individually by the operation of their cams, as 5, thereon, they will feed the yarn to the 85 cylinder needles and draw the new loops through the old. The cylinder needles being of the latch type operate in the ordinary manner. They are individually operated as is usual, and they are fed with yarn by the 90 spring beard needles as the latter retract, as shown in Fig. 3^a.

Pressing of the needle beards is done by a presser member 13 having a bevelled lower edge for engaging the spring beards of the 95 needles. This presser is in the form of a plate of somewhat elongated form extending along the circular needle row and conforming in curvature thereto. It is held by a screw 14 to the dial cap. This plate serves 100

not only as a presser member for the spring beard needles, but also as a latch guard for the latch needles, as will be clear from Fig. 4.

It will be understood that by using spring beard needles together with latch needles finer gauges of fabric are obtainable than would be possible if both sets of needles were latch needles. Further by using latch needles for one row, presser means for this row is eliminated. There is no problem of dividing the old from the new loops for pressing on a second row of spring needles, as the latch needles inherently take care of the trapping of the new yarn with their latches as in ordinary practice. Further by employing the latch needles in the cylinder and the spring beard needles in the dial, visibility of and access to the knitting elements is obtained for the reason that the sinkers operate vertically and the bed and cam ring therefor are below the plane in which the spring beard needles work, and are substantially no higher than the verge of the cylinder and dial. The sinkers are spaced considerably apart from the cylinder, thus enhancing visibility of the knitting elements. The cam ring for the sinkers furnishes a support for the heads of the advanced spring beard needles and sustains them against the thrust of the yarn when carried across their stems by the sinkers.

By the use of the spring beard needles together with latch needles, the advantage is gained that latch interference, such as takes place when two sets of latch needles are used, is avoided, particularly in fine gauges.

The yarn guide tube is carried by a finger piece or button 15 turnable in a bracket 16. By turning this finger piece, the yarn guide tube can be moved out from under the hook of the sinker so that threading of the yarn can be done. The finger piece when turned can be lifted and held by a bayonet joint structure of any suitable form. When dropped down again, a spring 18 will throw the yarn guide finger into position for feeding the sinkers, i. e., under the hooks thereof as shown in Fig. 3.

The so-called bayonet lock for this yarn feed device consists of a pin 18^x extending across the bracket 16 in opening 16^x to co-operate with cut away portions 19 and 20 in the side of the cylindrical portion of the finger piece. These cut away portions 19 and 20 lie at an angle to each other as shown in dotted lines in the plan view of the finger button.

Means are provided for raising and lowering the dial and dial cap relative to the cylinder so that access readily may be had to the knitting elements, particularly the needles of the cylinder. For this purpose the dial 3 is pinned at 21 to a post. This post at its upper end has pinned thereto at 21^a the gear 22 by which the dial post with its dial

is driven, it being understood that the machine is of that type in which the needle cylinders revolve and the cams remain stationary, though the invention is not limited to this type of machine in all of its aspects. This gear 22 has its hub supported by a ball bearing organization 23 which in turn rests upon the upper end of a sleeve 24 having a head or flange 25 at its upper end, in a recess of which the ball bearing organization 23 is supported. Secured to the flange 25 are rack or toothed bars 26 which extend down through openings in the fixed frame member 27, which is supported by posts as at 28 from the base of the machine. These rack bars are engaged by a screw thread 29 on the interior of a gear 31. This gear rests upon the upper end of the hub 27^a of the frame member 27 and it is operated by a pinion 30 engaging the teeth 31 thereof. The pinion is mounted on a shaft 34 which has its bearings in a bracket 32 and at 33 in the hub 27^a of the spider frame 27. The bracket 32 depends from the guard ring 35 which shields the gear 22. This guard ring is supported from the spider frame 27 by posts, two of which are shown at 36. The shaft 34 is operable by a hand crank 37. By turning this crank the gearing is operated to make the internal screw thread 29 of the gear 31 lift the rack bars 26, thus raising the sleeve 24 and the hub of gear 22, which in turn lifts the dial post which is pinned to the hub at 21^a. Lifting of the post thus raises the dial and its cap. The means for rotating the cylinder may be of any well known arrangement and need not be illustrated here.

In order to adjust the dial with its cam cap relative to the needle cylinder, the upper end of the dial post is reduced and threaded at 38 and a nut 39 having a graduated ring 40 serves as the means for accurately setting the dial post at the desired elevation.

The nut 39 will be turned in relation to any suitable mark or marks on the hub of the gear 22.

As in usual practice, the gear 22 is operated from any suitable pinion or gear so that the cylinder and dial will rotate in unison. The dial cap may be held in fixed position by any suitable bracket or link connection with the main frame, as in ordinary practice, as is well known.

In Fig. 2 I have shown the proper relation of the toothed bars or racks to the spider frame work 27. That is to say, the toothed bars are located on radii intermediate the radially extending arms of the frame.

In Fig. 1, however, and merely for convenience of illustration, these toothed bars are shown as though located in the same radial planes with the arms of the spider frame.

I claim:

1. A rib knitting machine in which spring beard needles operate in a horizontal plane,

sinkers operating in a vertical plane for feeding the yarn to the spring beard needles, and latch needles operating in a vertical plane and to which the spring beard needles feed the yarn, substantially as described.

5 2. A rib knitting machine, having a row of spring beard needles and a cooperating row of latch needles said spring needles operating in a horizontal plane, sinkers for feeding the yarn to the spring beard needles, said sinkers extending and operating in a vertical plane, and having overhanging hooks at their upper ends, cam means below the plane of the horizontal spring beard needles 10 for operating the sinkers, and means for feeding the yarn beneath the overhanging hooked ends of the sinkers, substantially as described.

15 3. A rib knitting machine having a cylinder and dial, spring beard needles in the dial, latch needles in the cylinder, vertically operating sinkers having upper overhanging hooks, cam means below the plane of the horizontal spring needles for operating the sinkers, means for feeding yarn beneath the hooks of the sinkers, a presser for the needle beards, said presser extending in front of the latch needles and serving as a latch guard therefor, substantially as described.

20 30 4. A rib knitting machine comprising spring beard needles in one row, means for operating said needles individually, latch needles in the other row with means for operating said needles individually to cooperate with the spring beard needles for making rib fabric, sinkers having overhanging hooks to feed the yarn to the spring needles, means for feeding the yarn under the hooks, and means for operating the sinkers located on 25 the side of the needles opposite that upon which the hooks of the sinkers normally lie, said spring needles feeding the yarn to the latch needles.

35 40 In testimony whereof, I affix my signature.
45 KENNETH HOWIE.
